Filed Dec. 10, 1962, Ser. No. 72,793

Term of patent 7 years

(Cl. D45—4)

FIG. 1

FIG. 2

FIG. 3

FIG. 4

FIG. 1 is a top plan view of a link chain for a bracelet, showing my design;

FIG. 2 is a top plan view on an enlarged scale of one of the links of the link chain of FIG. 1;

FIG. 3 is a side elevational view of the top shell of one of the links of the link chain of FIG. 2; and

FIG. 4 is an end elevational view, on a further enlarged scale, of the top shell of the link chain of FIG. 2.

The shading shown in the drawings represents contrast.

I claim:

The ornamental design for a link chain for a bracelet or the like, as shown and described.
